WITNESS:

UNITED STATES PATENT OFFICE.

MAURICE W. WATERS, OF DETROIT, MICHIGAN.

DESK CALENDAR.

1,406,120.

Specification of Letters Patent. Patented Feb. 7, 1922.

Application filed April 11, 1921. Serial No. 460,343.

To all whom it may concern:

Be it known that I, MAURICE W. WATERS, a citizen of the United States, residing at Detroit, in the county of Wayne and State 5 of Michigan, have invented new and useful Improvements in Desk Calendars, of which the following is a specification.

This invention comprehends the provision of a desk calendar, wherein the indicia with 10 regard to the month, day and year is carried by endless belts movable within a casing and adapted to be presented to view through suitable sight openings formed in the casing.

The nature and advantages of the invention 15 will be better understood when the following detailed description is read in connection with the accompanying drawing, the invention residing in the combination, construction and arrangement of parts as 20 claimed.

In the drawing forming part of this application, like numerals of reference indicate similar parts in the several views and wherein:

25 Figure 1 is a top plan view of the calendar constructed in accordance with my invention.

Figure 2 is a vertical sectional view therethrough.

30 Figure 3 is a longitudinal sectional view through the calendar.

Referring to the drawing in detail, 10 indicates the bottom 10 of a casing having front and rear walls 11 and 12 respectively 35 which are connected by end walls 13. The rear wall 12 projects a slight distance above the front wall 11, and the top 14 is thus arranged at an angle or inclination as shown. The rear wall may be used as a name plate.

40 Arranged within the casing are spaced partitions 15 which divide the casing into separate compartments, and at the same time form bearings for the rollers 16. These rollers 16 are journaled within each compartment adjacent the corners thereof, and over each group of rollers is trained an endless belt. The belt 17 of one compartment contains indicia relative to the months of the year, while the belt 18 in the adjacent compartment carries indicia relative to the days 45 of the month, while in the final compartment there are two endless belts 19 and 19' trained over the rollers, and each having numerals

in consecutive order from one to zero. The top 14 is formed with eight openings 20 55 above each compartment, and each sight opening is closed by a pane of glass or other suitable transparent material 21. By reason of this fact the indicia carried by the belts in the respective compartments can be 60 readily viewed. The glass 21 in the final compartment, or in other words wherein the endless belts 19 and 19' are arranged, has painted or otherwise arranged thereon the numeral "19," which numeral co-operates 65 with the numerals carried by the endless belts 19 and 19' to indicate the year.

The front wall 11 is formed with spaced vertically disposed slots 22, and projecting through each slot is a knurled disk or the 70 like 23 through the instrumentality of which the endless belts are manipulated to bring to view before the sight openings the proper month, day and year. Each of these disks 23 is associated with one of the rollers 16 so 75 that the endless belts can be easily adjusted for the purpose above mentioned. The invention is not only simple in construction, but its design makes it particularly advantageous as a desk ornament, in addition to 80 serving the purpose for which it is intended.

While it is believed that from the foregoing description the nature and advantages of the invention will be readily apparent, I 85 desire to have it understood that I do not limit myself to what is herein shown and described, and that such changes may be resorted to when desired as fall within the scope of what is claimed.

90 What I claim is:
A device of the class described comprising a casing having an inclined top provided with a plurality of openings and having a plurality of spaced vertically disposed slots formed in the front wall thereof, a plurality 95 of spaced partitions disposed in said casing, a plurality of rollers journaled in suitable bearings in said partitions adjacent to the front and rear walls of said casing, a plurality of endless belts surrounding said rollers bearing suitable indicia, and a plurality of knurled disks extending through said slots and adapted to engage said belts.

100 In testimony whereof I affix my signature.

MAURICE W. WATERS,
